US00D996880S

(12) **United States Design Patent** (10) **Patent No.:** **US D996,880 S**
(45) **Date of Patent:** **** Aug. 29, 2023**

(54) **BEVERAGE MAKER**

(71) Applicant: **OTFES CO., LTD.**, Taoyuan (TW)

(72) Inventor: **Chih-Te Lin**, Taoyuan (TW)

(73) Assignee: **OTFES CO., LTD.**, Taoyuan (TW)

(**) Term: **15 Years**

(21) Appl. No.: **29/770,807**

(22) Filed: **Feb. 17, 2021**

(30) **Foreign Application Priority Data**

Aug. 24, 2020 (TW) 109304778

(51) **LOC (14) Cl.** **07-01**

(52) **U.S. Cl.**

USPC **D7/300**; D7/309; D7/310

(58) **Field of Classification Search**

USPC D7/300, 304, 307, 309, 310, 311, 312,
D7/316, 319, 323, 354, 397, 400;
D12/400; D23/207, 209; D24/162;
D34/39

CPC A47J 31/407; A47J 43/105; A47J 41/0038;
A47J 31/468; B65D 77/0406

See application file for complete search history.
